UNITED STATES PATENT OFFICE

PERCIVAL S. TICE, OF CHICAGO, ILLINOIS, ASSIGNOR TO STEWART-WARNER CORPORATION, OF CHICAGO, ILLINOIS, A CORPORATION OF VIRGINIA

CARBURETOR

Original application filed November 29, 1926, Serial No. 151,287. Divided and this application filed December 5, 1929. Serial No. 411,800.

This application is a division of my pending application Serial No. 151,287, filed November 29, 1926.

The purpose of the invention is to provide an improved construction in a carburetor for an internal combustion engine, for which purpose the invention consists in the elements and features of construction shown and described as defined in the claims.

10 In the drawings:

Figure 1 is a top plan view of a carburetor embodying this invention.

Figure 2 is a section at the line 2—2 on Figure 1.

15 Figure 3 is a section at the line 3—3 on Figure 2.

Figure 4 is a section at the line 4—4 on Figure 2.

20 Figure 5 is a section at the line 5—5 on Figure 2.

Figures 6, 7 and 8 are diagrammatic views of the nature of sections of the fuel mixture conduit and the entrance elbow thereto of several experimental forms by means of 25 which the effective form for certain of the purposes of this invention has been developed.

Figure 9 is a section at the line 9—9 on Figure 4.

30 Figure 10 is a diagrammatic view for showing the fuel conduits and their inter-relationship.

Referring to the drawings for specific description of the construction by which the 35 purpose of the invention is accomplished:

The carburetor shown in Figure 1 has its fuel mixture conduit, 1, discharging at the engine intake and provided intermediately in its course with a constricting sleeve, 2, 40 hereinafter called the throat sleeve, and which may be somewhat of Venturi form, and with a throttle valve, 3, between said throat sleeve and the engine intake, constituting therefore a posterior throttle.

The fuel element of the fuel mixture is derived from a fuel chamber shown as a level-governing chamber or "float bowl", 5, to which the fuel is supplied from a main 50 tank or like source, not shown, by gravity or

other pressure through the inlet passage, 5^a, the admission of fuel to the fuel chamber, 5, being controlled by a float-operated valve, 6, the construction of the float and connections for such control being fully described and covered by my said parent application Serial No. 151,287, and requiring no description for the purpose of the present invention, which relates to other parts of the construction; and for the purposes of the invention to be covered in this application, it is only important to note with respect to this float bowl and connections that the fuel flow from the fuel chamber to the mixing chamber of the carburetor ordinarily, that is, for main supply to the carburetor in the ordinary operation of the engine when running under load with wide open throttle, is by way of metering plug, 40.

This metering plug, 40, is inserted at the 70 entrance to a short horizontal bore, 41, in a boss, 15, formed on the carburetor body, and thence up through a vertical bore, 42, in said boss to the intersection of said vertical bore with a horizontal bore, 42^a, through which the fuel passes to an annular channel formed by a peripheral groove 43, encompassing the throat sleeve, 2, and communicating with both ends of a duct, 44, extending through the entire length of a bridge, 45, which is 75 formed integrally with said sleeve and extending diametrically across the throat.

The fuel flowing through the duct, 44, is discharged in the throat of the fuel mixture conduit through a plurality of ports, 45^a, 80 which are distributed substantially uniformly along the length of said bridge, 45, opening upwardly from said duct, 44. (See Fig. 3.)

For engine idling, an auxiliary fuel passage is provided leading to a second annular channel formed by a second groove, 50, encompassing the throat sleeve, 2, at a short distance above the groove, 43, to which channel, 50, the fuel is led from a restricted port, 46, opening from the fuel chamber into a vertical bore, 47, (see Fig. 2) leading up to a horizontal bore, 51, which discharges into said second groove, 50. The bore, 47, is formed by drilling in from the top of the cast- 95 100

ing, and the bore is threaded at the upper part for receiving the threaded stem of a needle valve, 53, which seats at a port, 54^a, formed through a metering plug, 54, which is interposed in said passage, 47, said valve stem having a knob handle, 55^a, for manual adjustment of the valve to control, according to the judgment of the operator, the flow capacity of the auxiliary passage.

- 10 The knob-handle co-operates with a spring-pressed detent, 57, whose upper end engages counter-sinks, 55^b, in the under side of the knob handle to hold the valve yieldingly at the position at which it may be set for regulating the flow of capacity of the port, 54^a.
 15 From the channel, 50, apertures, 58, are made opening into the fuel mixture conduit throat at opposite sides thereof and at positions adjacent to the ends of the bridge, 45.
 20 Said auxiliary passage, 50, is rendered operative for furnishing an idling fuel supply, by cooperation of a duct, 60, formed in the wall of the fuel mixture conduit, 1, leading down from a port, 61, which is formed open-
 25 ing into the fuel mixture conduit beyond the seating position of the throttle, 3, and at its lower end communicating through a cross bore, 64, with said second or auxiliary channel, 50, said cross bore opening into the channel, 50, preferably directly opposite the discharge ports, 58.

The manner of functioning of this construction is that when the throttle valve is closed for idling of the engine, the relatively high vacuum resulting at the engine intake beyond the closed throttle, causes fuel to be sucked up through the auxiliary passage, 51, together with limited quantity of air drawn in through the ports, 58, affording a suitably rich mixture for idling.

Upon opening the throttle somewhat, from its idling position, the increased air flow through the throat, together with the actuation of the fuel supply accelerating diaphragm, 93, hereinafter described, causes fuel discharge from the bridge ports 45^a.

Under condition of lesser throttle opening, the fuel thus delivered would accumulate on the bridge to a considerable depth before being carried away by the main air stream past the bridge; and the manner of its delivery would be irregular, were it not for the action of the air ports, 58, into which such fuel is drawn as soon as it begins to accumulate on the bridge. The ports, 58, and associated passages leading to the "beyond-throttle region" pick up and deliver quickly, and in a relatively finely divided state, fuel delivered to the throat by the bridge ports, 45^a, whenever the depression across the ports, 58, is sufficient to cause flow into them from the throat.

Upon the throttle being opened fully for running at speed with load, the pressure at the ports, 58, and at the bridge ports, 45^a, becoming lower than that at the port, 61, all the fuel

is fed into the air stream at said ports, 58 and 45^a.

Pressure-operated devices, including the diaphragm, 93, above referred to, for impelling auxiliary fuel supply for discharge into the fuel mixture conduit anterior to the throttle, which are shown in the drawings of this application, are fully shown, described and claimed in my pending application Serial No. 136,251, filed September 18, 1926, and these parts and devices will be now briefly described introductory to certain detail description of the additions and modifications of these devices which will be pointed out as the description proceeds.

At each side, front and rear, of the carburetor at the neck of the casting which connects the body of the float bowl with the fuel mixture conduit, there is formed a diaphragm-partitioned chamber of which the cavity at one side of the partitioning diaphragm is formed by a recess in the face of the casting, and the cavity at the other side of the diaphragm is formed by a corresponding recess in the face of an applied cap, 91, the diaphragm-partition being clamped between the margins of the cavities as the cap is applied and bound in place by securing bolts.

In the drawings, (see Figure 4) the pair of partitioned cavities at the front side are seen respectively at 90 and 90^a, in the body casting, 92, and in the cap, 91, partitioned from each other by the flexible diaphragm, 93. Corresponding cavities at the rear side of the body casting are seen at 110 in the body casting, and at 112 in the cap, 111, said cavities being partitioned from each other by the diaphragm, 113. A plunger, 96, having its stem, 95, mounted in the cap and pressed inwardly by a spring, 91^a, tends to hold the diaphragm, 93, flexed inwardly for reducing the capacity of the cavity, 90.

The diaphragm, 113, partitioning this rear pair of cavities is bound, as to the main central part of its area, between the heads, 115 and 115^a, of two stems or plungers, 116 and 116^a, the former being spring-pressed outwardly by the spring, 117, and the latter being arranged to be thrust inwardly by one end of a lever, 150, which is pivoted at 151 on the cap, 111, and which is actuated at its opposite end by a cam, 152, on the protruding end of the throttle valve stem, 3^a.

A bore, 99, extending through the body casting, intersecting the bore, 42^a, puts the cavities, 90 and 110, in communication with the annular channel, 43, and with the duct, 44, and discharge apertures, 45^a, of the bridge, 45, and thereby operates for discharge of fuel in the fuel mixture conduit anterior to the throttle.

The fuel reaches the cavity, 90, by way of ports, 120, leading to the inner end of the bore, 121, in which a hollow plunger, 122, having one end lodged against the diaphragm,

93, for action of the diaphragm on the plunger, 122, as hereinafter referred to, has its axial cavity communicating with the cavity, 90, by ports, 123, the entrance to said plunger cavity,—the port, 124,—being controlled by a valve, 125, having a slender stem, 126, protruding through the port, 124, toward which the valve is spring-pressed by a spring, 122^a, reacting between the inner end of the valve and an adjusting screw, 128, which is set in the end of the plunger.

In the construction as thus far described, the valve, 125, would be always closed, preventing access of fuel to the cavity, 90, but for provision for causing said valve to be limitedly open to a degree variable by manual adjustment according to the requirements and judgment of the operator, said provision consisting in a ball, 130, lodged at the entrance to the bore, 121, in which the plunger, 122, reciprocates, but not obstructing fuel flow into said bore.

Against this ball the stem, 126, of the valve, 125, is stopped, so that upon the inward flexure of the diaphragm, 93, the valve seat, 124, having the port, is withdrawn from the valve, admitting flow of fuel into the cavity, 90. A cone-pointed adjusting stem, 135, set up through the under side of the body casting, has its cone point, 136, in position for encountering the ball, 130, at the side opposite the stem of the valve, 125, and adapted for screwing in or out to adjust the ball for positioning the valve, 125, so that the port, 124, shall be opened more or less widely at a given inward flexure of the diaphragm 90.

The fuel reaches the cavity, 110, by way of the port, 132, which is controlled by a check valve, 131, seating against return flow to the float bowl.

A duct, 140, is formed in the wall of the fuel mixture conduit parallel to the duct, 60, and about 90 degrees around from the latter, 45 said duct, 140, being connected at its upper end by an oblique duct, 141, leading into the fuel mixture chamber beyond the seating position of the throttle valve.

At its lower end, the duct, 140, is intersected by a horizontal duct, 142, opening out through the annular encompassing wall of the cavity, 90, registering with the duct, 143, in the annular encompassing wall of the cavity, 92, in the cap, 91, which latter duct 55 opens into said cavity, 92; and a thimble, 144, extending through the diaphragm, 93, at the marginal portion thereof at which it is clamped between the encompassing walls of the cavities, 90 and 92, respectively, 60 bridges the junction of the two ducts, 142 and 143 at their registered ends.

This bridging of the junction of the two ducts, 142 and 143, at their registered ends, ensures continuity of the pressure passage 65 from the post-throttle region of the engine

intake, and is communicated to the cavity, 92, for flexing the diaphragm, 93, to reduce the cavity, 90, whereby said pressure forces the fuel from the cavity, 90, by way of passages, 99 and 42^a, for discharge at the bridge 70 apertures, 45^a.

For rendering substantially effective for its purpose, the construction shown, consisting in distribution of fuel ports along the bridge, 45, a corresponding distribution of 75 the air flow so as to be substantially uniform over the entire cross section of the fuel mixture pipe throat, is necessary. I have ascertained by experiment that in the case of air driven or drawn,—and particularly if drawn, 80 as by suction,—through a pipe elbow of uniform cross section throughout the bend, as in the diagrammatic view of Figure 6, or having uniformly diminishing,—conical,—cross section from entrance to discharge or 85 connection with the fuel mixture conduit throat, as in the diagram Figure 7, the air current does not leave the elbow in lines parallel to the axis, but on the contrary, the air current tends toward the outer side of 90 the elbow bend; and if such elbow in a carburetor connection is directly coupled with the fuel mixture throat, the current leans off toward the side opposite the intake of the elbow, as indicated by arrow lines, 200, in 95 Figure 7.

I have found that it is not possible to correct or overcome this deflection so as to cause the current to enter the conduit throat in true axial direction as is necessary in order to distribute itself uniformly through the cross section of the throat, by giving the elbow a conical tapered terminal for connection with the throat as illustrated in Figure 6; but on the contrary with such connection the air 100 stream is deflected to the opposite side of the elbow, as indicated by arrow lines, 201, in 105 Figure 6.

I have found that the desired result of uniform distribution of the air flow over the 110 cross section of the throat with minimum eddying and internal turbulence in the air stream, is obtained by shaping the elbow to contract the cross sectional area as the discharge into the throat is approached, and effecting this contraction by curving the outer convex side of the bend with a radius less than required for contracting the passage uniformly. The result, as seen in Figure 8, is a well-rounded blending of the elbow 115 section with the throat section, in which the curve, 202, shows the form of elbow of uniform cross section throughout, from which the actual outline deviates for contracting by curving with a radius less than would yield uniform contraction, as may be understood by comparing the successive radii, indicated at 203, in Figure 8, taken at equal angular intervals, the center of the outer curve being 120 offset in the plane of the junction of the elbow 125 130

with the straight portion from the axis of the straight portion a distance equal to the difference in the diameter of the inner and outer ends of the elbow, as may be seen in Figure 8.

I claim:

1. In a carburetor and the like for an internal combustion engine, in combination with a fuel mixture conduit comprising a throat through which the fuel mixture moves toward the engine intake, a fuel supply passage discharging in the conduit throat, said passage comprising a channel encompassing the throat, the conduit having a hollow bridge extending diametrically across the throat, the cavity of the bridge communicating at both ends with said throat-encompassing channel, and having a plurality of ports distributed along the length of the bridge for delivery 20 of fuel onwardly in the conduit.

2. In a carburetor, a fuel mixture conduit comprising a throat through which the fuel mixture moves toward the engine intake having at the throat a relatively narrow bridge 25 extending across the throat-way, hollow from end to end, and a channel in the wall of the throat at the transverse plane at which the bridge is located adapted for connection with a fuel supply passage, said channel communicating with the cavity of the hollow bridge, the bridge having a plurality of fuel discharge ports leading from its cavity, distributed along its length for distributing the fuel discharge over the cross section of the 30 throat.

3. In the construction defined in claim 2, the fuel mixture conduit having its throat formed by means of a sleeve fitting liquid-tight in the conduit, the channel being formed 40 as a groove in the outer surface of the sleeve encompassing the conduit, the conduit wall having a fuel duct which terminates in a port registering with said groove.

4. In a carburetor and the like for internal 45 combustion engines, in combination with a fuel mixture conduit comprising a throat through which the fuel mixture moves towards the engine intake, a fuel supply passage discharging in the conduit throat, the 50 conduit having a hollow bridge extending diametrically across the throat, said passage comprising a channel communicating with both ends of the cavity of the bridge and said bridge having a plurality of ports distributed along the length of the bridge for delivery of fuel onwardly in the conduit.

5. In a carburetor, a fuel mixture conduit forming a throat through which the fuel mixture is directed towards the fuel intake, a 55 hollow fuel feeding bridge extending diametrically across the throat, said bridge having a plurality of discharge ports distributed along the length thereof and a fuel supply 60 passage including portions in communica-

tion with the opposite ends of said hollow bridge.

6. In a carburetor, a vertical fuel mixture conduit, a throat, an air intake elbow communicating at one end with said throat, a fuel supply passageway leading to the throat, a hollow bridge extending diametrically across the throat perpendicular to the plane of the bend of the air intake elbow, said bridge having a plurality of discharge ports distributed along the length thereof, said fuel supply passage being in communication with the opposite ends of said hollow bridge, the air passage through said elbow being tapered narrowing throughout the bend, the outer curve having an approximate uniform radius about a center in the plane of the junction of the elbow with the straight portion of the throat and offset in that plane away from the axis of said straight portion past the center of curvature of the inner side of the elbow a distance equal to the difference in diameter of the outer and inner ends of the elbow due to the taper.

7. In a carburetor, a vertical fuel mixture conduit, a throat, an air intake elbow communicating at one end with said throat, a fuel supply passageway leading to the throat, a hollow bridge extending diametrically across the throat perpendicular to the plane of the bend of the air intake elbow, said bridge having a plurality of discharge ports distributed along the length thereof, said fuel supply passage being in communication with the opposite ends of said hollow bridge, the air passage through said elbow being tapered narrowing throughout the bend of the elbow, the outer curve of the elbow being so much offset from the center of the inner curve and with such a radius as to cause the elbow passage to taper narrowing at an increasing rate from the outer end to a point in the outer curve at which a tangent thereto is parallel to the axis of the throat.

In testimony whereof I have hereunto set my hand at Chicago, Illinois, this 29th day of November, 1929.

PERCIVAL S. TICE.
